*Winfield H. Taber
by B. J. Hayes, atty.*

UNITED STATES PATENT OFFICE.

WINFIELD H. TABER, OF BOSTON, MASSACHUSETTS.

DESIGN FOR A CORNER-BLOCK FOR MATTRESS-FRAMES.

SPECIFICATION forming part of Design No. 26,245, dated November 3, 1896.

Application filed August 10, 1896. Serial No. 602,367. Term of patent 7 years.

To all whom it may concern:

Be it known that I, WINFIELD H. TABER, a citizen of the United States, residing at Boston, in the county of Suffolk and State of Massachusetts, have invented and produced a new and original Design for Corner-Blocks for Mattress-Frames, of which the following is a specification, reference being made to the accompanying drawing, showing a part thereof.

5 The drawing shows in perspective a corner-block for mattress-frames, showing my design.

The leading feature of my design consists in a cubical or box-like structure open at the top and at one side and having an annular or socket-like formation at one corner.

5 *a b c d* represent four sides of a cubical

structure which is open at the top and one side, and at the lower right-hand corner of said box-like structure, being at the junction 20 of the sides *c* and *d*, is an annular or socket-like formation. A hole *f* appears at the upper left-hand corner of the side *a*.

I claim—

The design for corner-blocks for mattress- 25 frames herein shown and described.

In testimony whereof I have signed my name to this specification in the presence of two subscribing witnesses.

WINFIELD H. TABER.

Witnesses:

B. J. NOYES,
HARRY O. ROBINSON.
